ELECTRIC BROILERS

Peter G. Pritz, Jenkintown, Pa.

Application April 24, 1957, Serial No. 654,802

2 Claims. (Cl. 74—626)

The object of the invention is to provide improvements in food broilers broadly speaking, but more especially in the rotary type in which units of the substances being broiled are continuously revolved about individual axes corresponding with a single unit or group of such units, in which will be referred to as a planetary orbit or path about axis that is common to a multiplicity of such units or groups of units, whereby the individual units in both cases are subjected upon all sides to the heat emanating directly from one or more electric heat sources, as well as by convection and normal circulation from them, this application being a continuation-in-part of copending application, Serial No. 510,886, filed May 25, 1955, now Patent No. 2,855,842, issued October 14, 1958.

The improved device has been so designed as to include all of the advantages of the original development, but in addition thereto includes a combined operating and control mechanism that has proved to be more efficient than the first, and at the same time more simple in construction and operation, while costing substantially less to manufacture, and at the same time minimizing any tendency to require repair and replacement after long and continued use.

Another object is to provide a device of this nature, which essentially comprises at least one revolvable disk, spider, or equivalent rotatable primary support, at least one auxiliary support carried by such primary support and itself being revolvable about an axis that is parallel with but spaced from that of said disk or the like, in combination with means to secure either one or a plurality of frankfurters to said auxiliary support, a fixed annular rack which cooperates with and is in engagement with said auxiliary support during a major portion of its normal orbital movement about said primary support, and means to regularly disengage said auxiliary support from said rack through a limited portion of its orbit, during which time treated frankfurters may be removed from, and fresh frankfurters attached to, said last-mentioned support.

A further object of the invention is to directly drive one of the auxiliary supports while the normally revolvable disk and spider are disconnected from the motor.

With the objects thus briefly and broadly stated, the invention comprises further details of construction and operation, which are hereinafter brought out in the following specification, when read in conjunction with the accompanying drawings, in which Fig. 1 is a front elevation of a broiler comprising one embodiment of the invention; Fig. 2 is a right hand elevation of the same; Fig. 3 is a left side elevation of the same; Fig. 4 is a horizontal section on the line 4—4 of Fig. 1; Fig. 5 is an enlarged front elevation of the exterior of the clutch mechanism for controlling the operation of the motor driving system; Fig. 6 is a plan view of said driving system with the protective casing removed; Fig. 6a is a fragmentary view showing both sides of the pivotal connection between the members 33 and 34 and the motor support 35; Fig. 7 is a fragmentary portion of the same

2

but with the control in a different position; Fig. 8 is a fragmentary view showing the normal intermeshing engagement of the rack and pinion driving means, that normally connect the primary and auxiliary units; Fig. 9 is a fragmentary view showing the gravitydrop that arrests the backward rotation of an auxiliary unit with respect to said primary unit when they are out of mesh and ready to have sausage or the like placed on or removed from them; and Fig. 10 is a fragmentary side elevation of a portion of the mechanism shown in Fig. 6.

Referring to Figs. 1, 2, 3 and 4, one embodiment of the invention is shown as comprising a lower chamber having an open front 1 (Fig. 1), a closed rear wall 2a, a left hand transparent side panel 2 (Fig. 3), a sheet metal right end wall 3 (Fig. 2), and metallic corner angles 4 connecting and fixedly positioning said panel walls. The bottom of said chamber is closed by a wall 5, while the top is preferably covered by a top wall 6 above which is a suitable hollow closure 6a, in which rolls, bread slices, or the like, may be warmed by the heat that escapes and naturally rises from the broiler below, and while protected from the surrounding dust-laden atmosphere, said closure preferably comprising an inverted hollow container that is hinged at 7 to the body of the broiler, and maintained by gravity in normally closed position.

Within said broiling chamber and revolvably supported by and between the opposite side walls 2 and 3 is a main shaft 8 to the left end of which (within said chamber) is secured a spider 9, having angularly related radial arms 10 and a corresponding disk 10a on the right end, while said shaft 8 projects freely through said right end wall. Said shaft may be manually rotatable from the left side by means of a knob 11 upon the outside of the transparent wall panel 2, while the opposite right hand end of the said shaft is normally rotated by a motor and intervening control mechanism hereinafter described. Extending between the arms of said spider and said disk are a plurality of auxiliary shafts 13, each of which is provided with a plurality of longitudinally spaced pairs of radially projecting sharpened pins 14, upon which frankfurters or so-called "hot dogs" 15 are impaled, as shown in Fig. 1, parallel with said auxiliary shafts. By this means of mounting them, the frankfurters revolve about the axes of said auxiliary shaft 13, while these supporting shafts normally revolve about the common axis of the main shaft 8, in what is generally known as a planetary motion or orbit.

In the upper portion of the broiling chamber and immediately below the top wall 6 is a zig-zag electrically energized heating unit 16, whose ends extend through the right hand side wall 3 and are provided with terminals 17 for connection to suitable controls and eventually to a twin-wire connection cord and plug connector or the like 18, the flow of current to said heating unit being controlled by a conveniently located switch 18a, and the desired temperature maintained by an adjustable knob 18b. Also within the upper portion of said broiling chamber are one or more incandescent lamps or the like 19, for aiding in the proper positioning and finally the extraction of the broiled food products. Electrical connections and the improved driving mechanism are enclosed within and protected by a removable hollow casting 20, that is secured in position by means of a pair of finger-actuatable knurled nuts 21, and is provided with an enlarged circular aperture 22 and an arcuate aperture 23 for purposes hereinafter described.

Secured to yet spaced from the outer surface of the right side wall 3 is a secondary wall plate 24, which shields the orbital rotating mechanism (Figs. 6, 7 and 8). This mechanism essentially comprises the disk 10a that is secured to and revolves with the shaft 8 within a circu-

lar cutout 26 in said side wall, and said disk also serving as a support for the adjacent end portions of the auxiliary shafts 13. These last-mentioned shafts carry upon their outer ends gears 27, that normally mesh with corresponding teeth upon the periphery of a much larger gear or circular rack 28. Rack 28 is secured to the wall plate 24 in order to prevent it from losing or altering its angular position and are provided with radially enlarged flanges 29, that maintain said gears in the plane of said rack, and with hubs for a purpose hereinafter referred to. The apertures 30 in said revolvable disk 10a, through which the end portions of said auxiliary shafts revolvably extend, are radially elongated, so as to permit said shafts 13 to be lifted individually from engagement with said rack 28, with which they are respectively in normal engagement under the yielding force of a flattened wire spring 31, and from which they are periodically released during a short portion of their major orbit by any suitable means, such as an abbreviated fixed cam surface 32 with which they are in engagement for a short time, while the respective auxiliary shaft is in a forward position in which the frankfurters upon such shaft may be removed and fresh frankfurters may be made to replace them.

Upon the outer side of and spaced from said secondary wall plate 24 is fixedly positioned another plate 33 of less extent, and to this last-mentioned plate is pivotally secured at 34 a frame 35, that supports at one end an electric motor 36, which through a series of speed-reducing gears 37, 38, 39 and 40 and their intermediate smaller pinions rotates a shaft 41, whose inner end carries a gear 42. When said frame with its motor and gears is in its upper position (Fig. 10), the slowest-speed gear 42 is in mesh with and directly drives a large gear 43, carried by the main shaft 8 and thereby rotates the composite broiling unit as a whole. But when said frame is rotated angularly about the pivot 34 in counterclockwise direction, when viewed from the right as in Fig. 10, the driving gear 42 is lifted freely out of mesh with the gear 43 and the broiler unit ceases to revolve, while the motor continues to revolve uninterruptedly. This oscillatory motion of said frame is effected by means of a forwardly extending lever 44, carrying a manually engageable actuating knob 45 upon its free end, and which lever is engageable with spaced steps or notches 46, 47 and 48, with which a bracket 48a is provided. This bracket forms a freely outwardly projecting extension of the plate 33, and said lever being permitted to move outwardly from its normal position adjacent to said motor-gear unit against the tension of a light spring 49 that surrounds the screw 34a, while the opposite or relatively fixed end of said lever is loosely secured to said motor-gear frame by means of a bolt or the like 50. Said lever is provided with an upwardly projecting spur 51, that when in its uppermost position is pressed inwardly by the spring 49 to the rear of an annular flange or shoulder 52 of a knob 53, secured to the outer free end of a pin 54, that is normally maintained in its outermost inactive position by means of a coil spring 55, so that its bifurcated opposite end 56 is normally free from engagement with all of the diametrically extending lugs 56a of the several gears 27 of the respective secondary planetary shafts 13, but which pin, when in its innermost or left hand position against the tension of said spring, is engageable with one of said gear lugs and thus permits manual rotation of the engaged planetary shaft by means of the knob 53, to permit the removal from and attachment of frankfurters to such shaft, while its particular gear 27 is free

from engagement with the rack 28 by means of the cam 32.

When it is desired to attach frankfurters to or remove them from an auxiliary shaft, the knob 45 of the lever 44 is depressed until said lever engages the intermediate notch 47, which disconnects the motor and its gear chain from the large main shaft gear 43, so that rotation of said main shaft 8 immediately ceases, manual reverse rotation of the knob 11 permits reverse rotation of said main shaft, until such rotation is stopped by the forwardmost and most accessible gear collar 27a being engaged by cam surface 32 and by a shoulder 58 of a pawl 59, that is pivotally mounted at 60 upon the side walls 3, in which position the adjacent auxiliary or secondary shaft lug 56a of the shaft 13 is coaxial with the lug 56 of the pin 54, and said pin is thereupon capable of being shifted axially inwardly into engagement with said lug, and manual angular adjustment of the aligned shaft 13 is permitted, in order to thereby make possible the attachment or detachment of frankfurters relative thereto, as hereinbefore described. When it is desired to drive an auxiliary shaft individually, the gear collar 27a is rotated into the manually adjustable position being engaged by cam surface 32 and by shoulder 58 of pawl 59. The knob 45 of lever 44 is then depressed until the lever engages the lowermost notch 48 which causes gear 42 of drive means 36-41 to mesh with the gear on pin 54. The pin 54 is engaged with an auxiliary shaft 13 causing the latter to rotate individually.

Having thus described my invention, what I claim and desire to protect by Letters Patent of the United States is:

1. A broiler, comprising the combination of a horizontal shaft provided with a coaxial gear, a series of auxiliary shafts parallel and equally spaced from said horizontal shaft, means for connecting said auxiliary shafts to said horizontal shaft, means for revolving said auxiliary shafts in parallel planetary orbits relative to said horizontal shaft, each of the shafts of said series having an engageable surface, a frame, means for oscillating said frame in a plane transverse to and about an axis eccentric to the axis of said first shaft, a motor driven series of gears carried by said frame and one of said gears being engaged with said coaxial gear, a lever transversely movable with respect to and extending freely from said frame with which it is fixed against movement parallel with the plane of said frame's oscillating movement, said lever being operative to remove said gear from engagement with said coaxial shaft, a pin, means for reciprocating said pin, said pin being coaxially related to one of the gears of said series and when in one position being engageable selectively with the end surface of one of the shafts of said series, enabling it to be manually activated, said lever in one position being operative to prevent the movement of said pin into engagement with said last-named shaft while said coaxial gear is engaged by said series gear.

2. A broiler according to claim 1, in combination with means to limit reverse rotation of said unit when said gear series is disengaged from said coaxial gear until one of said auxiliary shafts' end surface is in operative coaxial alignment with said stud.
